UNITED STATES PATENT OFFICE.

ROY L. BECK, OF TRENTON, MISSOURI.

WATER PUMP FOR TRACTORS.

1,406,524.

Specification of Letters Patent. Patented Feb. 14, 1922.

Application filed November 29, 1920. Serial No. 427,150.

To all whom it may concern:

Be it known that I, ROY L. BECK, a citizen of the United States, residing at Trenton, in the county of Grundy and State of Missouri, have invented certain new and useful Improvements in Water Pumps for Tractors, of which the following is a specification.

This invention relates to means for filling the cooling systems of combustion engines or other mechanisms which require cooling, and the primary object of this invention is to provide an improved mechanical device for filling the radiator of tractors, thereby eliminating the time and inconveniences generally associated with the filling of the radiators by hand.

In tractors, the radiators are positioned relatively high and as the same require a great quantity of water which varies according to the horse power or size thereof considerable labor and trouble is experienced in filling the radiator. It is therefore another prime object of the invention to provide a water pump associated with the tractor and driven by the engine thereof for filling the radiator mechanically.

Another object of the invention is to provide an improved means for mounting the pumps upon the tractor frame, and an improved means for bringing the pump into and out of operative engagement with the engine, so that the pump can be readily brought into or out of operation by the driver of the tractor from the driving platform or seat.

A still further object of the invention is to provide an improved mechanical device for filling radiators of tractors, of the above character which will be durable and efficient in use, one that will be simple and easy to manufacture, and one which can be placed upon the market and incorporated with a tractor at a reasonable cost.

With these and other objects in view, the invention consists in the novel construction, arrangement and formation of parts as will be hereinafter more specifically described, claimed and illustrated in the accompanying drawings, forming a part of this specification, in which drawings:

Figure 1 is a side elevation of a tractor showing the improved water pump incorporated therewith, and illustrating the means of connecting the intake pipe of the pump with a water tank or stream.

Figure 2 is an enlarged fragmentary longitudinal section through a tractor frame illustrating the means of connecting the pump therewith, parts of the pump being shown 60 in section.

Figure 3 is an enlarged fragmentary transverse vertical section through a portion of the tractor frame illustrating the means of connecting the pump thereto, the pump 65 being shown in edge elevation.

Figure 4 is a detail perspective view of the guide employed for slidably mounting the pump upon the tractor frame.

Referring to the drawings in detail, 70 wherein similar reference characters designate corresponding parts throughout the several views, the letter A indicates a tractor and B the improved mechanical water pumping means therefor.

The tractor A may be of any preferred construction or make and as shown includes the frame 5, having the usual side channel beams 6, the engine 7, and the radiator 8 therefor. The frame 5 has mounted thereon 80 in the usual manner the front steering wheels 9 and the rear traction wheel 10.

The engine 7 is provided with the usual crank shaft 11, upon which is mounted the fly wheel 12, which is utilized in this invention for driving the mechanical water pumping device B.

The radiator 8 is mounted in the ordinary manner on the front of the frame 5 and is connected with the water jacket of the engine by the usual pipes 13. An ordinary filling spout 14 is provided for the radiator, so that the same can be filled by hand when desired, and the radiator adjacent to the rear end thereof is provided with an elbow 95 joint coupling 15 with which the mechanical filling means B is adapted to be associated.

The improved mechanical pumping means B includes a guide 20 which is adapted to be bolted or otherwise secured as at 21' to 100 one of the side channel beams 6 of the tractor frame 5 adjacent to and in front of the fly wheel 12 for the engine. The guide 20 consists of a base plate 21 and a right angularly related flange 22. This flange 22 forms 105 the means by which the guide block may be secured to the side channel beam. The upper surface of the base plate 21 is provided with a longitudinally extending dove tailed groove 23, which forms a guide track for the 110 centrifugal water pump 24, which forms the pumping means for the mechanical filling

device B for the radiator. The pump 24 includes a stator 25 having a base 26, which is substantially dove-tail shaped in cross section as at 27 for engaging in the dove tailed groove 23. It is preferred that the dove tailed groove 23 and the dove tailed tongue 27 be machined, so that the pump may be easily slid back and forth in the groove. This pump 24 may be of the ordinary or any preferred construction and the operating shaft 28 thereof has the rotor of the pump mounted thereon in the usual manner. The lower end of the stator 25 is provided with the usual outlet nipple 30, 10 while the hub of the stator is provided with an intake nipple 31. The drive shaft 28 for the pump has keyed or otherwise secured thereto a friction pulley wheel 32, which is adapted to engage the periphery of the fly 15 wheel 12.

The pump 24 is adapted to be connected to the radiator 8 by means of a vertically disposed pipe 35, which is connected to the elbow joint coupling 15. The lower end of the pipe 35 has an elbow joint 36, which is adapted to receive the flexible hose section 37, which is connected to the outlet nipple 30. A flexible hose section 38 is detachably connected to the inlet nipple 31 and this hose section is adapted to be inserted into a water tank designated by the numeral 39 or into any stream, from which the radiator is to be filled.

A means C is provided for sliding the pump 24, so as to bring the friction pulley wheel 32 into and out of engagement with the periphery of the fly wheel 12, so that the pump can be brought into or out of operation when desired.

This means C includes a hand lever 40 which is pivotally mounted adjacent to its lower end upon a stationary sector rack 41 which is secured in the driver's cab or adjacent to the driver's seat. The lever is adapted to be held in its adjusted position by means of the usual dog and rack mechanism. The lower end of the lever has connected thereto a connecting rod 42, which is secured by means of a pivot bolt 43 to a rearwardly 50 extending lug 44 carried on the base of the stator 25.

It can be seen that by shifting the lever the pump can be moved back and forth.

When the pump is to be used, the removable hose section 38 is connected to the inlet nipple 31 and the lower end of the hose is placed in the water supply. The lever 40 is then shifted so as to move the pump 24 rearwardly until the pulley 32 engages the periphery of the fly wheel, at which time the pump will be operated. The pump as stated, is of the usual or any preferred construction and the water is pumped in through the inlet nipple 31 and forced out of the outlet 65 nipple 30, through the vertically disposed

pipe 35, the elbow coupling 15 and into the radiator. An ordinary gauge 45 is provided for the radiator, so that the amount of water therein can be readily determined.

From the foregoing description, it can be seen that an exceptionally simple and durable means has been provided for mechanically filling the radiator of tractors, thereby eliminating the trouble and discomfort generally experienced in the filling of radiators for tractors.

Changes in details may be made without departing from the spirit or scope of this invention; but,

I claim:

1. In a device for mechanically filling radiators of the cooling systems of an internal combustion engine, the combination with a motor vehicle including an internal combustion engine and a cooling system having a radiator, of a filling device for the radiator including a water pump having an inlet and an outlet nozzle, means for connecting the water pump to the vehicle, means for operatively connecting the pump to an operating part of an engine, means for connecting the outlet nozzle to the radiator, and means for connecting the inlet nozzle to a water supply.

2. In a device for mechanically filling radiators of the cooling system of an internal combustion engine, the combination with a motor vehicle including a radiator, of a filling device for the radiator including a water pump having an inlet and an outlet nozzle, means for slidably mounting the pump on the motor vehicle, means connecting the outlet nozzle with the radiator, means for connecting the inlet nozzle with a water supply, and means for bringing the water pump into and out of operative engagement with an operating part of an internal combustion engine.

3. In a device for mechanically filling radiators of the cooling system of an internal combustion engine, the combination with a motor vehicle including a combustion engine, and a cooling system therefor having a radiator, of a filling device for the radiator including a water pump, a guide block secured to the motor vehicle, means slidably connecting the pump to the guide block, a pipe system connected to the radiator, a flexible hose coupling connecting the pipe system with the outlet port of the pump, means for connecting the inlet port of the pump with a supply tank, and a lever for bringing the pump into and out of operative engagement with an operating part of an internal combustion engine.

4. In a device for mechanically filling radiators of the cooling system of an internal combustion engine, the combination with a motor vehicle including a combustion engine and the cooling system therefor having

- a radiator, of a filling device for the radiator including a water pump, a guide block secured to the motor vehicle, means slidably associating the water pump with the guide block, the water pump having an inlet and an outlet nozzle, a pipe system communicating with the upper ends of the radiator, a flexible pipe connecting the outlet nozzle with the pipe system, means connecting the 5 inlet nozzle with the water supply, a lever arranged adjacent to the driver's seat of a motor vehicle, means for holding the lever in an adjusted position, and a rod connecting said pump with the lever.
- 10 5. In a device for mechanically filling radiators of the cooling systems of internal combustion engines, the combination with a motor vehicle including a chassis having side beams, an internal combustion engine having 20 a cooling system including a radiator, the internal combustion engine including a crank shaft having a fly wheel, of a device for filling the radiator including a pump having inlet and outlet nozzles, a block secured to one side beam, means slidably associating the pump with the block, the pump having a drive shaft, a friction pulley secured to said drive shaft arranged in direct 25 alignment with the fly wheel, means connecting the outlet nozzle with the upper end of the 30 radiator, means connecting the inlet nozzle with the water supply, and means for sliding the pump to bring the friction pulley wheel thereof into and out of engagement with the periphery of the fly wheel. 35
6. As a new article of manufacture, a mechanical filling device for radiators of the cooling systems of internal combustion engines comprising a base plate, a water pump, means for slidably connecting the 40 water pump with the base plate, the water pump having inlet and outlet nozzles, means for shifting the position of the pump on the base plate, as and for the purpose specified. 45
7. As a new article of manufacture, a mechanical means for filling the radiators of tractors comprising a guide block adapted to be secured to a tractor frame, the block having its upper surface provided with a dove tailed groove, a pump including a base 50 having a dove-tailed tongue formed thereon arranged to be slidably mounted in said groove, inlet and outlet nozzles formed on said pump, a rearwardly extending apertured lug formed on the pump base, a 55 pivoted operating lever, and means pivotally connecting the operating lever with the rearwardly extending apertured lug.

ROY L. BECK.
